RADIO CONTROL SYSTEM

Eugene F. McDonald, Jr., Chicago, Ill.

Application July 25, 1940, Serial No. 347,516

15 Claims. (Cl. 250—14)

This invention relates to a control system for a radio set and more particularly to an improved system by which certain functions of a radio receiving set may be controlled in a simpler and more expeditious manner.

The present invention is particularly useful in connection with radio receivers mounted in automobiles although it has general application wherever it is desired to control a radio receiver. The conventional hand tuning or actuation by hand of station selectors with conventional automobile radio receiver installations constitutes a serious hazard as the driver's attention is distracted and serious accidents have frequently resulted. Furthermore, it is many times important to mute the radio receiver for short periods of time in order to be able to listen for warning bells at railroad crossings or for the sounds of approaching vehicles or trains.

In accordance with the present invention, muting of the radio receiver for controlled periods of time as well as the selection of the desired signal to be received can be accomplished through a single member actuated, for example, by foot control with a special type of switch mounted on the floorboard of an automobile. This enables the control operations of the radio receiver, which ordinarily require close attention by the driver, to be carried out without requiring the driver to look at the radio set or remove either hand from the steering wheel.

In addition to the safety features above discussed the driver can easily mute the radio receiving set in order to engage in conversation with passengers and furthermore, a plurality of control devices can be employed so that control of the radio set may be accomplished from the rear seat or the passenger's side of the front seat, if desired.

It is, therefore, an object of the present invention to provide an improved control system for a radio receiving set.

Another object of the invention is to provide an improved safety control system for an automobile radio receiving set.

Another object of the invention is to provide an improved device for muting a radio receiver or selecting a desired signal or performing both of these functions simultaneously.

A further object of the invention is to provide a system for controlling changing the transmitting station being received and muting of the radio set from a remote point by a single actuating member.

Other objects and advantages of the invention

will appear in the following description of preferred embodiments thereof disclosed in the attached drawings of which:

Figure 1 is a schematic diagram of a radio set and control mechanism embodying the present invention.

Figure 2 is a vertical section through a switch mechanism which may be employed in the present invention.

Figure 3 is a horizontal section taken on the line 3—3 of Figure 2.

Figure 4 is a fragmentary vertical section taken on the line 4—4 of Figure 3.

Figure 5 is a vertical section through a modified form of mechanism adapted to be employed in the present invention.

Figure 6 is a fragmentary vertical section of the device of Figure 5 taken at right angles thereto.

Figure 7 is a horizontal section taken on the line 7—7 of Figure 5.

Figure 8 is a plan view of a releasing ring of the switch of Figure 5.

Figure 9 is an elevation of the locking sleeve of the switch of Figure 5.

Figure 10 is an elevation of the sleeve of Figure 9 taken at right angles thereto.

Referring to Figure 1, 15 indicates diagrammatically the various sections of a conventional radio receiving set. All of the circuits of the set are not shown but the circuits necessary for an understanding of the present invention are shown exteriorly of the diagrammatic representation 15 of the set. Thus, the antenna 16 and an antenna coupling and radio frequency tuning circuit 17 is shown connected to the radio frequency stage 35 of the set 15; an oscillator frequency control circuit 18 is shown connected to the oscillator and mixer section of the set, and an output circuit 19 is shown connected to the audio frequency section of the set. The antenna coupling and radio frequency tuning circuit 17 may include an antenna choke 20, an antenna coupling condenser 21, and a radio frequency tuning coil 22. One terminal of the coil 22 may be grounded at 23 and its other terminal connected to a movable contact 24 of a station selector switch 25. The stationary contacts A, B, C and D of the switch 25 may each be connected to one terminal of separate presetable condensers 26 which have their other terminal connected to ground at 27. The stationary contact M of the switch 25 may be connected to one terminal of a variable condenser 28 forming one condenser of a two condenser gang providing for manual or dial tuning of the set. The other terminal of the condenser 28

28 may be connected to ground at 29. A trimmer condenser 30 may be connected across the condenser 29. It is apparent that rotation of the switch 25 will selectively place a desired condenser 26 or condensers 28 and 30 across the tuning coil 22 to provide parallel radio frequency tuned circuits.

The oscillator frequency control circuit 18 may include a coil 31 which may have one terminal 10 connected through a condenser 32 to the plate or anode grid of an oscillator tube (not shown) and its other terminal connected to ground at 33. Such an arrangement can be employed with a shunt fed oscillator, although obviously the invention can be adapted to other types of oscillator circuits. The movable contact 34 of a second selector switch 35 may be connected to the grid of the oscillator tube (not shown) through a condenser 35'. Each of the stationary contacts A, B, C and D of the switch 35 may be connected to one terminal of separate presettable inductances 36 having their other terminals connected to ground at 37. The inductances 36 may be of variable permeability type in which an adjustable iron core is employed to preset the desired value of inductance. The contact M of the switch 35 may be connected to one terminal of a variable condenser 38, forming the other condenser of the two condenser gang, for manual tuning. The other terminal of the condenser 38 may also be connected to ground at 39 and a trimmer condenser 40 may be connected across the condenser 38.

The movable contact 41 of a third selector switch 42 may be connected to the movable contact 34 of the switch 35. Stationary contacts A, B, C, and D of the switch 42 may be connected to one terminal of a fixed condenser 43 having its other terminal connected to ground at 44. The contacts A, B, C, and D of the switch 42 may also be connected to one terminal of a coil 45 coupled to the oscillator coil 31 having its other terminal connected to ground at 46. The stationary contact M of the switch 42 may be connected to one terminal of a coil 47 coupled to the coil 31 and having its other terminal connected to ground at 48 through a tracking condenser 49. It will be apparent that simultaneous rotation of the switches 35 and 42 will selectively 45 connect the adjustable inductances 36 across the coil 45 and also across the condenser 43. The variable inductances 36, coil 45 and condenser 43 provide parallel grid circuit tuning circuits and adjusting the appropriate variable inductance 36 50 will provide the proper oscillator frequency for any desired station. When the switches 35 and 42 reach the contact M the variable inductances 36, condenser 43 and coil 45 are disconnected from the circuit and the manual tuning condenser 38 55 and the coil 47 are connected in parallel to form a parallel grid circuit tuning circuit for the oscillator frequency under control of the condenser 38. It is also apparent that an adjustable condenser 26 in combination with a corresponding 60 adjustable inductance 36 comprises a means for presetting the receiver for any desired station and that a plurality of such presettable means are provided. The tuning circuits described 65 above are given merely by way of example as many other types of tuning circuits involve adjustable condensers in both the antenna coupling circuit and the oscillator circuit as well as in other radio frequency circuits or involving 70 variable inductances in any of these circuits, as

well as variable inductances for manual tuning may be employed.

In accordance with the present invention, all of the switches 25, 35 and 42 may have their movable contacts mechanically connected by 5 means of a shaft 50 shown in dotted line. The shaft may be provided with a ratchet 51 for step by step rotation of the shaft 50 by means of a reciprocable solenoid core 52 provided with a pawl 53 pivoted thereto, the core and pawl being 10 returned to normal position by a spring 54. Energization of the solenoid coil 55 moves the core 52 and pawl 53 downwardly in Fig. 1 to rotate switches 25, 35 and 42, one step for each actuation of the solenoid. By employing another switch 56 having a movable contact 57 rotated by the shaft 50, one position of the shaft 50 may be utilized to disconnect the receiver from its source of power, thus the contacts O of the switches 25, 35 and 42 may be left unconnected 20 and a notch 58 in the movable contact of the switch 56 arranged to break contact with the stationary contact 59 thereof when the movable contacts of the other switches are in engagement 25 with the contacts O of these switches.

In accordance with conventional practice, the storage battery 60 of an automobile having one of its terminals connected to ground at 61 may be employed to energize the circuits of set 15. Thus, the battery 60 may have its other terminal 30 connected to the movable contact 57 of the switch 56 through an ignition switch 61 and a manually operated control switch 62 and stationary contact 59 of the switch 56 may be connected to the power supply of the radio set. 35

The solenoid coil 55 may likewise have one of its terminals connected to the battery 60 through the switches 61 and 62. The other terminal of the solenoid coil 55 may be connected through a thermal cutout 63 and conductor 63' to a stationary contact 64 of a foot actuated control switch 65 mounted upon the floorboard 65' of the automobile and having a movable member 66 connected to ground at 67. The switch 65 may have a muting contact 68 connected through a conductor 68' to one terminal of the voice coil 70 of the output circuit 19 of the radio set. The other terminal of the voice coil 70 may be connected to ground at 71. The muting contact 68 of the switch 65 may be positioned to be engaged by 50 the movable member 66 prior to engagement between the movable member 66 and the contact 64. Thus, initial movement of the member 66 of the switch 65 short circuits the voice coil 70 to mute the radio set. The muting system shown is extremely efficient and perhaps the simplest, but it is apparent that a switch may be employed to effect operation of any other desired means of muting a radio set. 55

As previously described, the most desirable position for the switch 65 is upon the floorboard in the driver's compartment of the car so as to enable actuation of the switch by the foot of the operator. However, the switch may be positioned in any of the passenger compartments of 65 the car or a plurality of switches connected in parallel may be employed. A second switch 72 is shown connected in parallel with the switch 65 and may be in all respects similar to the switch 65. 70

Since the solenoid coil 55 will ordinarily take a rather large value of current for operation of the solenoid, holding switch 65 in its fully actuated position might unduly discharge the battery or overheat the solenoid coil. Such actions may be 75

5 prevented by employing the thermal cutout 63 in series with the coil 55. This thermal cutout may include a heater resistor 73 and a snap action bimetallic element 74. Current flowing through the resistor 73 heats the bi-metallic element to cause it to snap away from the stationary contact 75. This breaks the circuit through the resistor 73 and solenoid coil 55 until the bi-metallic element has cooled sufficiently to again snap 10 back into engagement with contact 75. Each time the contact between the bi-metallic element 74 and 75 is broken and reestablished the solenoid coil 55 is energized to rotate the switches operated thereby, thus apprising the driver of the vehicle that he is holding the switch 65 in its fully actuated position. Also the time of current flow through the solenoid coil 55 is decreased. The thermal cutout 63 may be adjusted to give relatively slow action and used 15 purely as a safety device or it may be adjusted to provide rapid action whereby holding the switch 65 in its fully actuated position will rapidly step the switches 25, 26 and 42 until the desired station is reached, at which time the switch 20 65 may be released.

25 A preferred type of switch 65 is shown more in detail in Figures 2 to 4. This switch causes muting of the radio set upon partial depression and changing of the station being received upon 30 full depression and may comprise a casing 75 with the movable member 66 forming a cover for the casing 75. The casing 75 and movable member 66 may have lateral extensions 77 and 78 respectively, loosely secured together at 35 79 by a rivet or the like so that the movable member 66 may pivot about the rivet 79 when depressed by the foot of an operator of a vehicle. The movable member 66 may be held in its uppermost position by means of a spring 80 40 gaging an annular spring retainer 81 supported by the casing 75. The casing 75 may have an upwardly extending annular portion 81' slotted at 82 to receive projections 83 carried by a plate 84 of insulating material. The plate 84 is held 45 in its uppermost position by means of a spring 85 bearing against a shoulder 86 on the interior of a casing 75. The plate 84 may be held within the casing 75 by means of lugs 87 forming part 50 of the annular member 81 of the casing 75, the lugs being bent inwardly over the plate 84.

55 The plate 84 is provided with a central aperture 88 which is surrounded by the muting contact 68 comprising an annular metal member secured to the plate 84. The muting contact 68 is connected to the conductor 68' extending from the casing 75 between the extensions 77 and 78. The movable member 66 may be provided with a downwardly extending portion 91 having a contact member 92 secured thereto and with a 60 downwardly projecting annular portion 93 for contacting the muting contact 68 carried by the plate 84. The solenoid operating contact 64 connected to the conductor 63', also extending from the casing, is insulated from the casing 75 as 65 shown in Figure 2.

70 It will be apparent that partial depression of the movable member 66 against the force of the spring 80 will cause the annular member 93 of the movable member to first come in contact with the muting contact 68 of the plate 84. The movable member 66 is connected to ground as shown in Figure 1 and this contact completes a circuit from the conductor 68' to ground thus muting the radio set as shown in Fig. 1. Further, depression of the movable member 66 moves 75

the plate 84 against the force of the spring 85 until the contact 92 of the movable member engages the contact 64 to complete a circuit from conductor 63' to ground, which as shown in Fig. 1 completes the circuit through the solenoid coil 55. The spring 80 is preferably a light spring requiring only a slight amount of pressure to actuate the movable member into contact with the muting contact 68. The spring 85 is preferably much stronger than the spring 80 so that 10 considerably more pressure is necessary to force the contact 92 into engagement with the solenoid operating contact 64. The operator of the switch can thus readily actuate the switch to mute the radio set without changing stations or 15 alternatively can operate the switch to change stations. The radio set remains muted during station changing and by only partially releasing the switch, not far enough to break the muting circuit, the operator may cycle the station selecting apparatus through several stations while 20 holding the radio set muted.

An alternative form of switch is disclosed in Figs. 5 to 10. With this type of switch partial actuation of the switch will mute the radio set 25 and retain the set muted after the switch has been released. A subsequent, partial or full actuation of the switch will release the muting contact. Such full actuation will also change stations. Also, a full actuation of the switch at 30 any time will change stations and release the muting of the radio set when the switch is released irrespective of the condition of the switch at the beginning of the full actuation.

The switch of Figures 5 to 10 may include a 35 casing 95 provided with a movable member 96 telescoping therewith and held in its uppermost position by a spring 97. The movable member 96 is held in position upon the casing 95 by means of screws 98 extending into slots 99 in 40 the casing to enable downward movement of the movable member 96. The movable member may have secured thereto a central circular member 100 by means of contact member 101. A sleeve member 102 shown more clearly in Figures 9 45 and 10 may surround the circular member 100 and be urged upwardly by means of a spring 103. The sleeve may be provided with a plurality of spring fingers 104 formed from the metal of the sleeve. In the uppermost position of the sleeve 50 50 the spring fingers 104 have their upper portions 104' compressed within slots 105 in an aperture in a plate of insulating material 106. The plate 106 is slidably mounted in the casing 95 and held in its uppermost position by a spring 107. Initial 55 downward movement of the movable member 96 drives the sleeve 102 downwardly to an intermediate position where the spring fingers 104 spring outwardly and latch under the insulating plate 106. The initial downward movement of 60 the sleeve brings the lower portion 108 thereof into contact with spring muting contacts 109 carried on a metal sleeve 110 insulated from the casing 95. The sleeve 110 is connected to the conductor 68' so that a circuit is completed from 65 the movable member 96, which is grounded, to the conductor 68'. Upward movement of the movable member 96 leaves the sleeve 102 in its intermediate position by compressing the spring 103 since the sleeve is latched in this position by 70 its spring fingers 104. This leaves the radio set in muted condition.

75 As shown in Figure 6 which is a partial vertical section at right angles in view of Figure 5, a member 110 is secured between the movable mem-

ber 96 and the circular member 100 and provided with spring fingers 111 which are resiliently urged inwardly toward the sleeve 102. In the normal or completely off position of the switch shown in Figures 5 and 6 the spring fingers 111 are held outwardly in the position shown in Figure 6 by lugs 112 struck outwardly from the sleeve 102. When the sleeve 102 has been latched in its intermediate position by the spring fingers 104 and the movable member 96 allowed to return to its upper position, the spring fingers 111 move inwardly above the lugs 112. Subsequent partial depression of the movable member 96 moves the sleeve 102 to a lowermost position still keeping the radio set muted. A releasing ring 113 held centered by lugs 114 extending upwardly through apertures in the plate 106 cams the spring fingers 104 inwardly during this further movement of the sleeve and holds the same in their inward position. The spring fingers 111 engaged above the lugs 112 on the sleeve are at the same time cammed outwardly by cam members 115 carried by the insulating plate 106 so as to clear the lugs 112, the lugs 112 being positioned between the small cams on the cam members. This releases the sleeve 102 which is then forced upwardly by the spring 103 into its intermediate position with the spring fingers 104 thereof carrying the releasing ring 113. If the movable member 96 is then released, this motion of the sleeve continues until the upper portions 104' of the spring fingers 104 are positioned within the slots 105 in the plate 106 and the sleeve is in its uppermost position so that the muting circuit is broken. During the latter part of this upward movement the releasing ring 113 is stripped from the upper portions 104' of the spring fingers 104 by the plate 106 so as to condition the fingers to be again latched under the plate 106. Thus, a second partial actuation and release of the movable member 96 allows the sleeve 102 to return to its uppermost position breaking the contact between the lower portion 108 of the sleeve 102 and muting contacts 109 to remove the muting action on the radio set.

If the movable member 96 is completely actuated at any time depending portions 116 (Fig. 5) upon a member 117 also secured between the circular member 100 and the movable member 96 engage the plate 106 after initial movement of the movable member and depress the plate against the action of the spring 107. Complete actuation of the movable member 96 brings the contact member 101 carried thereby into contact with a stationary contact 118 insulated from the casing and connected to the conductor 63'. Such complete depression of the movable member 96 will always move the sleeve 102 to its lowermost position so that upper portion 104' of the spring fingers 104 will always be engaged within the releasing ring 113. The sleeve 102, therefore, always returns to its uppermost position upon release of the movable member 96 after a complete actuation thereof. Nevertheless, the lower portion 108 of the sleeve 102 will be kept in contact with the contact members 109 during initial upward movement of the movable member 96 after complete actuation thereof so that the contact between contacts 101 and 118 may be repeatedly broken and reestablished without releasing the muting action. The solenoid coil 55 of Fig. 1 may thereby be repeatedly energized to step the switches through a plurality of steps while keeping the radio set muted.

It will, thus, be seen that partial actuation of

either the switch of Fig. 2 or the switch of Fig. 5 will first mute the radio set. Release of the switch of Fig. 2 after partial actuation will remove the muting action on the radio set whereas release of the switch of Fig. 5 will cause the radio set to remain muted until the switch has been again actuated. Both switches can be completely actuated to cause a station change. With both switches the radio set remains muted during the station changing operation and partial release of the switch followed by another actuation of the switch will cause a second station change while the radio set remains muted and this operation may be repeated as often as desirable. A complete actuation of the switches of either Fig. 2 or Fig. 5 and release of the switch will always remove the muting action from the radio set irrespective of whether the set was muted prior to such action.

Thermal cutout 63 of Fig. 1 may be employed with either type of switch as a safety or overload device for preventing excessive discharge of the battery 60 or burning out of the solenoid coil 55, by adjusting the same for slow relatively operation. It may also be employed both as a safety device and to secure a plurality of relatively rapid operations of the station changing mechanism by single depression of the main actuating switch. The former operation is preferred as an operator familiar with the station setting of a particular radio set may select any station with respect to the station previously being received by counting the number of complete actuations of the switch.

A plurality of switches such as those shown in Figs. 2 and 5, may be employed in parallel so that the receiver may be controlled from more than one point. In most installations the switch 56 for shutting off the radio set in one position will ordinarily be omitted and a lesser number of switch positions employed for a given number of stations. In any event, the system of the present invention enables station changing and muting of the radio set by a single foot operated control device without the operator having to look at the set or dial or remove his hand from the automobile controls. The system of the present invention is particularly applicable to the control of automobile radio sets and has been described in detail with respect to operation from low voltage batteries. However, other types of radio sets such as sets operated from alternating current or higher voltage direct current may be operated from a remote point in accordance with the principles of the present invention. The invention has been illustrated in connection with an "electrical" type of automatic tuning wherein individual presetable condensers or inductances are employed, but is also applicable to other types of automatic tuning arrangements.

While I have disclosed the preferred embodiments of my invention it is understood that the same is not limited to the details disclosed but may be varied within the scope of the following claims.

I claim:

1. An automobile radio receiving system comprising a receiving set having a plurality of presetable means for presetting said set to receive a signal from any one of a plurality of transmitting stations, selecting means for selecting a desired one of said presetable means, and means for operating said selecting means to select any one of said presetable means including a foot pedal positioned on the floor board of said auto-

mobile to be actuated by the driver of said automobile.

2. An automobile receiving system comprising a receiving set having a plurality of presettable means for presetting said set to receive a signal from any one of a plurality of transmitting stations, selecting means for selecting a desired one of said presettable means, and means for operating said selecting means to select any one of said presettable means including a solenoid for actuating said selecting means and a foot switch positioned on the floor board of said automobile to be actuated by the driver of said automobile for controlling the operation of said solenoid.

15 3. An automobile radio receiving system comprising a receiving set having a plurality of presettable means for presetting said set to receive a signal from any one of a plurality of transmitting stations, selecting means for selecting a desired one of said presettable means, muting means for said set, and control means for said selecting means and said muting means including a foot pedal capable of partial or full actuation and positioned at the floor board of said automobile to be actuated by the driver of said automobile, means for operating said muting means upon partial actuation of said pedal and means for operating said selecting means upon full actuation of said pedal.

30 4. An automobile radio receiving system comprising a receiving set having a plurality of presettable means for presetting said set to receive a signal from any one of a plurality of transmitting stations, selecting means for selecting a desired one of said presettable means, muting means for said set, and control means for said selecting means and said muting means including a foot pedal capable of partial or full actuation and positioned at the floor board of said automobile to be actuated by the driver of said automobile, means for operating said muting means upon partial actuation of said pedal and means for operating both said muting means and said selecting means upon full actuation of said pedal.

45 5. A radio receiving system comprising a receiving set having a plurality of presettable means for presetting said set to receive a signal from any one of a plurality of transmitting stations, muting means for muting said set, a step-by-step selecting means for selecting a desired one of said presettable means, and controlling means for said muting means and said selecting means including a movable member capable of partial or full actuation, and means for operating said muting means to mute said set upon partial actuation of said member and for both stepping said selecting means to select any one of said presettable means and operating said muting means upon full actuation of said member.

55 6. A radio receiving system comprising a receiving set having a plurality of presettable means for presetting said set to receive a signal from any one of a plurality of transmitting stations, muting means for muting said set, a step-by-step selecting means for selecting a desired one of said presettable means, and controlling means for said muting means and said selecting means including a solenoid for stepping said selecting means, a movable member capable of partial or full actuation, means for operating said muting means to mute said set upon partial actuation of said member, and means for operating both said muting means to mute said set and said solenoid to step said selecting means upon full actuation of said member.

7. In a system for controlling a radio receiver, a plurality of presettable means for presetting said receiver to selectively receive a signal from any one of a plurality of transmitting stations, step-by-step selecting means for selecting a desired one of said presettable means, muting means for said receiver, an actuatable member having at least two controlling positions, and means for operating said muting means without operating said selecting means at one controlling position of said member and for operating said muting means and stepping said selecting means at another controlling position of said member.

10 8. In a system for controlling a radio receiver, a plurality of presettable means for presetting said receiver to selectively receive a signal from any one of a plurality of transmitting stations, step-by-step selecting means for selecting a desired one of said presettable means, muting means for said receiver, a movable member having a normal position and actuatable through a first controlling position to a second controlling position, means for operating said muting means at said first controlling position of said member, means for operating both said muting and said selecting means at said second controlling position of said member, and resilient means resisting movement of said member from said normal to said first controlling position and resisting movement of said member from said first controlling position to said second controlling position with substantially greater force than from said normal position to said first controlling position.

15 9. In an automobile radio receiving system, a receiving set having a plurality of presettable means for presetting said set for selectively receiving a signal for any one of a plurality of transmitting stations, step-by-step selecting means for selecting a desired one of said presettable means, muting means for said set, a foot pedal having a normal position and movable from normal position through a first controlling position to a second controlling position, means for operating said muting means at said first controlling position of said pedal, means for operating both said muting means and said selecting means at said second controlling position of said pedal, resilient means resisting movement of said pedal from normal position, and means for abruptly increasing the resistance to movement of said pedal from said first controlling position to said second controlling position over the resistance to movement from said normal position to said first controlling position.

20 10. In a system for controlling a radio receiver, a plurality of presettable means for presetting said receiver for selectively receiving a signal from any one of a plurality of transmitting stations, selecting means for selecting a desired one of said presettable means, muting means for said receiver, and controlling means for said selecting means and muting means including an actuatable member having a normal position and movable from normal position through a first controlling position to a second controlling position, resilient means for resisting movement of said member from said normal position and returning the same to normal position, means for operating said muting means for muting said receiver upon a first movement of said member to said first controlling position, means for retaining said receiver in muted condition upon release of said member, means for releasing the muting of said receiver upon a subsequent movement of said member.

- member to said first controlling position and return to normal position and means for operating both said muting means and said selecting means upon movement of said member to said second 5 controlling position and for releasing the muting of said receiver upon full release of said member from said second controlling position irrespective of the condition of said muting means prior to the movement of said member to said second 10 controlling position.
11. In an automobile radio receiving system, a receiving set for receiving a signal from any one of a plurality of transmitting stations, muting means for muting said set, a foot pedal positioned 15 at the floor board of said automobile for actuation by the driver of said automobile for operating said muting means to mute said set, means for retaining the muting of said set upon release of said pedal after a first actuation thereof and 20 means for releasing the muting of said set upon a subsequent actuation and release of said pedal.
12. An automobile radio receiving system comprising a receiving set having a plurality of presettable means for presetting said set to receive 25 a signal from any one of a plurality of transmitting stations, selecting means for selecting a desired one of said presettable means, and means for operating said selecting means to select any one of said presettable means including a foot 30 pedal positioned at the floor board of said automobile to be actuated by the driver of said automobile, and means operated by said pedal for muting said set upon actuation of said pedal.
13. An automobile radio receiving system comprising a receiving set having a plurality of presettable means for receiving a signal from any 35 one of a plurality of transmitting stations, step- by-step selecting means for selecting a desired one of said presettable means, and means for stepping said selecting means to select any one of said presettable means including a foot pedal positioned at the floor board of said automobile to be actuated by the driver of said automobile, and means for stepping said selecting means through a plurality of steps upon a single actuation of said pedal. 5
14. In an automobile radio receiving system, a receiving set having a plurality of presettable means for receiving a signal from any one of a plurality of transmitting stations, electrically operated step-by-step selecting means for selecting a desired one of said presettable means including a stepping mechanism, a foot switch positioned at the floor board of said automobile to be closed by the driver of said automobile, a circuit between said stepping mechanism and said switch and means for stepping said selecting 15 means through a plurality of steps upon a single actuation of said pedal comprising a thermal element heated by current flowing through said switch for intermittently opening the circuit through said switch. 20
15. In an automobile receiving system, a receiving set having a plurality of presettable means for presetting said set to receive a signal from any one of a plurality of transmitting stations, a step-by-step rotary selecting device for 30 selecting a desired one of said presettable means, and means for rotating said device in steps to select any one of said presettable means including a foot pedal positioned on the floor board of said automobile to be actuated by the driver of 35 said automobile. 25
